WRENCH HAVING CONVEX FULCRUM
DETENT QUICKLY SHIFTABLE ALONG
HANDLE RACK

Nathan W. Warman, Los Angeles, Calif.

Application March 24, 1947, Serial No. 736,835

1 Claim. (Cl. 81—110)

1

This invention relates to a wrench to be used to clamp against, to hold, or rotate a round object such as a pipe or round bolt; in other words, to a wrench which is of a type commonly referred to as a Stillson wrench.

The user of a wrench of this type may be called upon to use the wrench on a small size pipe immediately after having used it on a pipe of much larger diameter. One of the objects of the present invention is to construct the wrench in such a way that the movable jaw of the wrench can be quickly adjusted to a position against the side of a pipe before the actual clamping action is applied to the wrench.

In applying the invention to a wrench such as referred to, I provide a lever, at the end of which a jaw is mounted or formed for engaging the side of a pipe, and the supporting means for the lever presents a fulcrum on which the lever is rocked when the clamping force is imparted to the jaw at the end of the lever.

One of the objects of this invention is to construct the lever and the fulcrum member in such a way that while an effective rocking movement can be attained, the lever can be readily shifted along over the fulcrum so as to bring the clamping jaw carried by it quickly in contact with the pipe, after which the force exerted laterally upon the lever, will operate to swing the relatively movable jaw toward the fixed jaw of the wrench, that is engaging the opposite side of the pipe; also to provide means cooperating with the lever to maintain the lever yieldingly in contact with the fulcrum.

Another object of the invention is to provide a wrench of this type, with a relatively movable jaw that is mounted on the end of the lever in such a way that it adapts itself automatically as it were, to the curved face of the pipe or other round object which is to be clamped, held, or rotated by means of the wrench.

Further objects of the invention will appear hereinafter.

The invention consists in the novel parts and combinations of parts to be described hereinafter, all of which contribute to produce an efficient quick-action wrench.

A preferred embodiment of the invention is described in the following specification, while the broad scope of the invention is pointed out in the appended claim.

In the drawing:

Fig. 1 is an elevational view, viewing the wrench from the side, but showing portions of the wrench partially in section as viewed on the section line

2

1—1 of Fig. 2. This view shows the inner end of the clamping lever partially in section, and also illustrates the wrench as applied to a pipe, which is shown in cross-section.

5 Fig. 2 is a plan of the wrench shown in Fig. 1, with the outer portion of the handle broken away.

Fig. 3 is a side elevation of the wrench head partially broken away, and shown in section. This view illustrates the shank of the lever disconnected from the fulcrum member on which it rocks, and in a position to enable the lever and its shank to be moved away from the fixed jaw to enable the wrench to be applied to a pipe of relatively large diameter.

15 Referring more particularly to the parts, the wrench includes a head 1 preferably having substantially the features of construction illustrated, that is to say, it includes a relatively fixed jaw 2, presenting a clamping face 3 with transverse ribs or serrations that particularly adapt it for engaging and biting into a side of a round object, such as a pipe 4.

The wrench head includes a guide extension 5, which is connected to the fixed jaw 2 by an integral neck 6. This guide extension presents a relatively wide slot 7, presenting two flat guide faces 8, between two side plates or "wings". The shank 10 of the wrench lever 11, is of substantially rectangular cross-section, and its side faces 20 fit neatly against the faces 8 of the guide extension 5. The slot or opening between the guide faces 8, is closed at the lower rounded, or lobed, end 12 of the wrench head, by a fulcrum member 13. This fulcrum member and the adjacent edge 14 of the shank 10, are constructed so that detent means on the fulcrum member can engage any of the teeth 15 that are formed along the edge 14. In order to effect this working connection between the fulcrum member 13 and the shank 10, I prefer

35 to employ a plurality of fixed teeth disposed on an arc and projecting from the adjacent edge 17 of the fulcrum member, and disposed on said arc in such a way that the edge 17 will not interfere with the free rocking movement, that is, a rolling movement of the lever on these teeth. In the present instance, I have illustrated three of these teeth 16, and I have disposed the edge 17 along a convex line or curve. This gives considerable clearance at the two points 18 and 19 between the curved face or edge 17 and the adjacent edge 14 of the shank. These detent teeth 16 are preferably inclined in the general direction of the fixed jaw 2, and the teeth 15 of the shank preferably incline in the opposite direction so that these teeth can interlock with each other in somewhat

3

the manner illustrated in Fig. 1; that is to say, the slanted faces of the teeth on the rack, rest adjacent to the inclined faces of the teeth 16, while the abrupt faces or shoulders 20 of the sets of teeth, engage each other in a manner to take the thrust developed by the reaction of the pipe against the end of the shank that carries the gripping means, or jaw, for engaging the adjacent side of the pipe.

If desired, the end of the shank 10 may have jaw teeth formed directly upon it, but I prefer to mount the relatively movable jaw 21 of the wrench on the end of the shank, by means of a pivot bolt 22. In order to effect this mounting, I prefer to form the jaw with side flanges 23 that lie against the side faces of the shank. In this way, a socket is formed at the back of the jaw to receive the end of the shank. The end face 10a of the shank is preferably slightly inclined and permits a slight amount of wobble of the jaw on the pivot. (See Fig. 1.) So, this jaw is freely movable through a small angle on the pivot 22, and its outer face or edge 24 is preferably concavely curved on a radius that is substantially as large as the radius of the largest size pipe on which the wrench is to be used. This concave face or edge 24 is provided with a plurality of serrations or teeth 25, which incline inwardly toward the neck 6 and away from the open side or throat 26 through which the pipe that is to be clamped, is introduced.

If desired, the fulcrum member 13 may be formed integrally with the wrench head, but I prefer to construct it as a separate piece that fits into place between the side plates or "wings" 9 of the wrench head, and secure the same in position by through bolts or rivets 27 that pass through the same.

The wrench is preferably provided with means for yieldingly holding the shank 10 with its serrated edge 14 in contact with the detent teeth 16 of the fulcrum member. For this purpose I may form the forward end of the slot 7, with an inclined edge or end face 28 to be engaged by one end 29 of a coil spring 30, the body of which is held on a through bolt or screw 31 that passes laterally through the neck portion 6 of the wrench head. The other end of this spring 30 extends longitudinally over the shank, and preferably is bent around to form a bight 32 that presses down against the adjacent edge of the shank.

Referring to Fig. 1, it will be evident that after the shank 10 is shifted toward the left (which is freely permitted by the inclined teeth) so that the movable jaw 21 engages the side of the pipe 4, if a force is applied to the outer portion or handle 33 of the wrench in the direction of the arrow indicated in Fig. 1, the shank 10 will rock on the teeth at 16 as a fulcrum, and this will move the inner end of the lever 11 toward the fixed jaw 2. As this end of the lever moves further into the throat, of course the concave edge of the movable jaw 21 will apply itself to the adjacent side of the pipe 4. This will jam the pipe against the fixed jaw 2, and clamp it firmly; and any increase in the force to rotate the lever 11 after the clamping action has occurred, will of course effect a rotation of the pipe on its own axis.

It will be evident that if the wrench lever is

4

swung back and forth, it will move freely on each backward swing, but will clamp the pipe and rotate it on each forward swing. This enables the wrench to operate with a ratchet-like action that is conducive to speed in operation.

The bolt 22 is of the same type as the bolt 31, that is to say, it has a threaded tip and a head at its other end, but in this case the head need not be countersunk into the side of the jaw. As the shank 10 completely fills the space between the inner faces 8, it will be evident that the jaw 21 operates as a stop to prevent the lever 11 from being accidentally pulled out of the wrench head. However, if it is ever necessary to remove the lever, this can be accomplished by taking out the bolt 22 and disengaging the jaw 21 before slipping the shank out of the head.

Many other embodiments of the invention may be resorted to without departing from the spirit of the invention.

I claim as my invention:

In a wrench, the combination of an integral U-shaped wrench head having inner and outer leg portions and a connecting web portion, a rigid jaw on said outer leg portion, a continuous longitudinal guide slot in said head extending from the free end of said inner leg portion to its other end and into said connecting web portion, a detent block mounted within said slot adjacent the free end of said inner leg portion, a handle with a shank having front and rear sides, and two flat sides for guided movement in said slot, said shank having a jaw secured to its inner end confronting said rigid jaw to cooperate with the same to clamp an object therebetween, said detent block having a convex edge disposed toward said shank with several inclined rack teeth formed on the same confined in extent to the middle portion thereof, said teeth inclining in the general direction of said first-named jaw; said front side of the shank having corresponding inclined rack teeth to engage the rack teeth of the block, and enable the shank to rock upon the same, a pin extending across the web portion of said slot beyond the rear side of said shank, and a spring mounted on said last named pin and exerting pressure on said shank to urge the same toward the block; fastening means for securing said block rigidly in the slot at said outer leg portion, said guide slot providing an unobstructed space back of said shank permitting said shank to be moved back at will at all times to disengage its teeth from said detent block.

NATHAN W. WARMAN.
